(57) **CLAIM**

The ornamental design for a shifter charm, as shown and described.

DESCRIPTION

FIG. 1 is a perspective view of a shifter showing my new design in the context of a vehicle center console; and

FIG. 2 is a perspective view thereof;

FIG. 3 is a front elevation view thereof;

FIG. 4 is a rear elevation view thereof;

FIG. 5 is a left side elevation view thereof; and,

FIG. 6 is a right side elevation view thereof.

The broken line in the drawings illustrate portions of the shifter and an environmental vehicle center console that form no part of the claimed design. The dot-dash broken lines in the figures depict a boundary of the claimed design and form no part of the claimed design.
